CLAIM

The ornamental design for a play mat set, as shown and described.

DESCRIPTION

The design comprises a play mat assembled from interlocking smaller mats having different ornamental designs on their top surfaces.

FIG. 1 is an exemplary construction of the play mat set of FIG. 2, showing the individual elements forming the claimed design of the play mat set assembled in condition of use;

FIG. 2 is a top perspective view of the play mat set showing our new design;

FIG. 3 is another exemplary construction of the play mat set of FIG. 2, showing the individual elements forming the claimed design of the play mat set assembled in condition of use; and,

FIG. 4 is another exemplary construction of the play mat set of FIG. 2, showing the individual elements forming the claimed design of the play mat set assembled in condition of use.
